CLAIM

The ornamental design for a charger, as shown and described.

DESCRIPTION

FIG. 1 shows a top plan view of a charger;
 FIG. 2 shows a front plan view of the charger of FIG. 1;
 FIG. 3 shows a rear plan view of the charger of FIG. 1;
 FIG. 4 shows a bottom plan view of the charger of FIG. 1;
 FIG. 5 shows a right plan view of the charger of FIG. 1;
 FIG. 6 shows a left plan view of the charger of FIG. 1;
 FIG. 7 shows a front perspective view of the charger of FIG. 1; and,
 FIG. 8 shows a rear perspective view of the charger of FIG. 1.

The broken lines in the figures depict portions of the charger which form no part of the claimed design.
